Filed Aug. 1, 1966, Ser. No. 569,463
3 Claims. (Cl. 346—140)

This invention relates to apparatus for recording information and, in particular, to recording information in the form of electrical signals or pulses on paper or the like with ink.

More specifically, this invention relates to the art of recording facsimile signals with droplets of ink on paper or record receiving material in response to electrical signals received from a remote source. In the art of facsimile reproduction, the copy to be reproduced is scanned in a manner which will create electrical signals indicative of dark and light areas on the original copy. For example, a spot of light is moved across the surface of the document to be scanned and light reflected from the surface of the document is used to activate a photocell or similar device. When the light is reflected from a light colored spot on the paper, the photocell is actuated and when the light spot encounters a dark area on the paper, the photocell is not actuated thus electrical signals can be produced depending on whether or not the photocell has seen reflected light or in response to the amount of reflected light that the photocell has received. The electrical signals are transmitted to a remote location where they are translated into light and dark spots on a piece of paper to produce a facsimile of the original document. The present invention pertains to a device which is responsive to such signals to lay down a spot of ink on a sheet of material such as paper. Thus, if the scanning of the original document is in small incremental areas and electrical pulses indicative of dark areas are transmitted, then a drop of ink placed on the copy sheet which is in response to that signal will produce a dark area on the copy sheet in the same relative position as the incremental area scanned.

Although there are many ink depositing devices known in the art, the present invention provides a novel method for controlling the flow of the liquid or ink through a capillary by utilizing the forces created when an electric current is passed through a conductor in a magnetic field. In the present invention an electrical current is made to flow through a conductive liquid material which is positioned perpendicular to a magnetic field. The conductor, which in this case is the recording ink, will experience a force which will act perpendicular to both the current flow and the flux of the magnetic field. The force experienced is utilized to apply drops of ink to the surface of a paper or recording medium in response to the electrical current. Thus, if the electrical current applied to the conductive ink is related to the electrical pulses received, then the ink deposited will correspond to the incremental areas as scanned on the original document.

It is the principal object of this invention to produce a facsimile reproduction of an original document by means of ink droplets deposited on a sheet of paper or the like in response to electrical pulses.

It is a further object of this invention to deposit droplets of ink in accordance with the electrical signals.

It is a further object of this invention to provide a recording device which utilizes a magnetic field and an electric current in the recording medium to produce ink droplets in response to electrical pulses.

These and other objects of this invention are obtained by means of a capillary positioned adjacent to a copy sheet in a magnetic field and having a pair of electrodes capable of transmitting current through a conductive liquid in the capillary. Electrically pulsing the electrodes pro-

duces a force on the conductive liquid longitudinal to the direction of the capillary, resulting in movement and droplets of the liquid material onto the copy sheet.

For a better understanding of the invention as well as other objects and further features thereof, reference is had to the following detailed description of the invention to be read in connection with the accompanying drawings, wherein:

FIG. 1 is an isometric view of a recording device embodying the present invention.

FIG. 2 is a schematic cross-sectional view of an inking capillary used in the device shown in FIG. 1.

In facsimile recordings, marks are made on a sheet of copy paper in response to electrical signals received from a remote source. There are various approaches to producing the marks on the paper. For example, an electric spark may be used to produce a mark from carbon paper onto the copy paper, or an electrolytic reaction on the copy paper may be used to produce discoloration, or selectively discharging an electrostatic charge on a photoconductive surface, and, as in the present invention, selectively depositing droplets of ink in accordance with electrical signals.

The invention disclosed herein pertains to inking type or recorder and basically consists of supplying conductive liquid ink through a capillary to the surface of a copy sheet. The capillary is positioned in and perpendicular to a magnetic field and has an electric current passed through the ink perpendicular to the capillary. By pulsing the current passing through the ink, droplets are caused to be deposited on the surface of the paper or support material. FIGURE 2 shows the walls 10 of a capillary tube 12 and the north and south poles of a magnet 14 positioned adjacent to the capillary 12. The ink is intended to flow down through the capillary tube 12 into contact with the surface of the copy paper. The capillary is sized so that the ink will not flow without some added force. A pair of electrodes 16 and 18 extend through the walls 10 into contact with the ink inside the capillary. When an electric current is placed on the electrodes 16 and 18 through the ink and the capillary 12, the ink is caused to flow through the capillary depositing on the surface of the copy material.

It is well known that a current carrying conductor in a transverse magnetic field has a force exerted upon it. The magnitude of the force is dependent upon the strength of the field and the magnitude of the current. This is the principle which is the basis for the operation of electric motors and generators. It is also the principle upon which the present invention relies for the motive force which produces droplets to be deposited on the copy paper. In this application the current carrying conductor are the electrodes 16 and 18 and the conductive ink in the capillary 12. As seen in FIGURE 2, the conductive ink will form a closed circuit between the two electrodes 16 and 18. The transverse magnetic field is produced by the electro-magnets 14 placed on each side of the capillary 12 and connected to a source of electrical current, not shown. In FIGURE 1 a signal source 20 is connected to the electrodes 16 and 18 by a pair of lead wires 22 and 24, respectively. The electrical signal source 20 is only shown schematically since it does not constitute part of the invention herein and is well known in the art. The electrical signals can originate from a remote source such as a facsimile scanning device or may be produced from a computer or a magnetic tape storage device.

Referring to FIG. 1 there is a rotatable drum 24 adapted to have a sheet of paper or record receiving material wrapped about its outer surface. The drum 14 is journaled for rotation by a motor MOT-1 at a speed which is usually synchronized with the movement of an

original document past a facsimile scanning station at a remote location. The motor MOT-1 also drives a lead screw 26 which advances a support block or nut 28 along the length of the drum 24. The block 28 supports the capillary 12 adjacent to the drum 24. As the drum rotates through one revolution, one line or incremental area of the copy paper passes beneath the tip of the capillary 12, and as the lead screw rotates, the capillary 12 is advanced in even increments so that the entire sheet of copy paper is traversed by successive rotations of the drum 24. Above the capillary 12 there is mounted an ink reservoir 30 containing a supply of electrically conductive ink 32 such as, for example, Chart Recording Ink sold by the Esterbrook Company or any ink that has adequate electrical conductivity.

When an electrical pulse is produced in lines 22 and 24 through the electrodes 16 and 18, a force is created along the length of the conductor herein the electrode 16, the ink supply, and the electrode 18. With the magnetic field oriented so that the lines of force extend from left to right between the magnets as seen in FIG. 2 and the current flows from the electrode 16 to the electrode 18, then the force on the ink is produced in the direction which will cause the ink to flow towards the record receiving sheet. That is, as seen in FIG. 2, the force will be in the direction into the page.

To prevent plating-out of the electrode, or deposition of material from one electrode to the other during operation, both the direction of the current and the flux through the capillary may be reversed without changing the direction of force exerted on the ink. If the current passing through the electro-magnet is reversed periodically and the current passing through the ink is also reversed in synchronism with the magnetic field, the force on the ink will be in the same direction at all times. The function of each of the electrodes in the capillary will alternate between being a cathode and an anode thus preventing the plating-out of metal. It may be desirable to reverse the current in the electro-magnet and the signal current at the end of each line of scan or at the end of each document thereby reversing the cathode and the anode and preventing any plating-out of the metal.

While the invention has been described with reference to the structure disclosed herein, it is not confined to the details set forth, and this application is intended to cover such modifications or changes as may come within the purposes of the improvements or the scope of the following claims.

What is claimed is:

1. A recording apparatus of the type wherein information in the form of electrical signals is recorded on receiving sheets by the deposition of drops of ink including

a capillary tube positioned adjacent to a record receiving sheet with an open end closely spaced from the surface of the sheet, means to supply an electrically conductive ink to the capillary,

a pair of magnets positioned adjacent to the capillary in position to provide a field of flux at right angles to the capillary,

a pair of electrodes extending into the capillary into contact with fluid in the base of the capillary, and means to pass electrical current through the electrodes in accordance with electrical signals received which causes the ink to flow.

2. A recording apparatus of the type wherein information in the form of electrical signals is recorded on record receiving sheets or the like by deposition of drops of ink including

means to support a record receiving sheet,

a capillary tube capable of containing a conductive ink positioned adjacent to the support means and having an open end closely spaced from the surface of a record receiving member on the support means, means to supply electrically conductive ink to the capillary,

means to create a magnet field perpendicular to the capillary tube,

a pair of electrodes positioned perpendicular to the capillary and extending into the capillary into contact with the conductive ink therein,

means to electrically energize the electrodes in response to electrical signals, and means to produce scanning movement between the capillary and the support means.

3. The apparatus of claim 2 wherein the means to support a record receiving sheet includes a rotatable drum adapted to hold a record receiving sheet and the means to produce scanning movement between the capillary and the support means includes a dry means to rotate the rotatable drum and a means to move the capillary tube longitudinally along the surface of the drum as the drum is rotated to thereby advance the capillary a given distance for each revolution of the drum.
